U.S. Cl. D85—2

FIG. 1

FIG. 2

FIG. 3

FIG. 4

FIG. 5

FIG. 6

FIG. 7

FIG. 1 is a front perspective view of a cigarette case showing my new design;

FIG. 2 is another perspective view of the cigarette case of FIG. 1, but showing the cap removed;

FIG. 3 is a front, elevated view of the cigarette case of FIG. 1;

FIG. 4 is a view thereof as seen from the right side of FIG. 3, the opposite side being substantially a mirror image thereof;

FIG. 5 is a back view thereof;

FIG. 6 is a top view thereof; and

FIG. 7 is a bottom view thereof.

Portions of the case shown in FIGS. 1, 2 and 3 are stippled to indicate contrast in appearance, and portions of the front surface in FIGS. 1, 2 and 3 are diagonally lined to indicate transparency.

I claim:

The ornamental design for a cigarette case, as shown and described.
